UNITED STATES PATENT OFFICE.

VAN WERT BALDWIN JOHNSON, OF WASHINGTON, DISTRICT OF COLUMBIA.

CHUTE.

SPECIFICATION forming part of Letters Patent No. 696,683, dated April 1, 1902.

Application filed November 27, 1901. Serial No. 83,877. (No model.)

To all whom it may concern:

Be it known that I, VAN WERT BALDWIN JOHNSON, a citizen of the United States, residing at Washington, in the District of Columbia, have invented a new and useful Chute, of which the following is a specification.

The present invention relates to chutes, and while particularly designed for use in transferring coal from cars to wagons or like vehicles it will be apparent that it may be employed for other analogous purposes.

The ordinary method of handling coal is to run the cars containing the same on an elevated trestle or track, then dump the coal into the space beneath, from which it has to be shoveled by hand into wagons or carts. This latter operation is expensive, because of the amount of labor and time necessary; and the primary object of the present invention is to provide apparatus of an exceedingly simple character by means of which coal may be transferred directly from a car to a vehicle without any intermediate handling.

Coal when taken from the cars is disposed of in two ways, either being delivered directly to customers or placed in stock for future delivery. In the first instance it is immediately screened, while in the second it is not, for the reason that it soon slacks and upon its future delivery must needs be screened again. Therefore another important object of the invention is to provide apparatus for transferring coal which will either screen the same, and thus place it in proper condition for immediate delivery, or will leave it unscreened and in its original state.

The embodiment of the invention set forth in this application is at present considered most desirable; but the right is reserved to make such changes from the construction shown and described as the scope of the appended claims will permit.

In the accompanying drawings, Figure 1 is a perspective view of the chute applied to an elevated track. Fig. 2 is a longitudinal sectional view through the same. Fig. 3 is a cross-section taken on the line 3-3 of Fig. 2. Fig. 4 is a rear elevation of the chute with the screen removed. Fig. 5 is a perspective view of the screen and the slack-coal recep-

tacle detached from the body. Fig. 6 is a perspective view of a slightly-modified form of construction. Fig. 7 is a plan view of the screen-chute employed in connection therewith.

Similar numerals of reference designate corresponding parts in all the figures of the drawings.

In order to clearly illustrate the application of the invention, a portion of an elevated track or trestle is shown comprising stringers 10, on which are mounted the usual tracks 11, a platform 12 being located upon the trestle and having an opening 12^a. The apparatus is suspended from this trestle beneath the platform and is preferably constructed in the following manner:

An inclined body formed of sheet metal or other material and rectangular in cross-section comprises spaced side walls 13, connected at their upper edges by a top 14, said top and sides being riveted or otherwise secured together. In the form shown in the first five figures a solid bottom 15 is secured between the side walls and above their lower edges, this bottom being preferably parallel with the top and forming an inclosed chute 16, having its upper and lower ends open. The upper ends of the side walls are provided with outstanding flanges or elbows 17, which are secured to the under side of the platform at the edges of the opening, and the bottom 15 is likewise provided with an outstanding flange or elbow 18, which is attached through the medium of a bracket 19 to one of the stringers 10. The lower end of the body is supported by hanger-braces 20, secured at their lower ends, preferably, though not necessarily, to the top 14, and at their upper ends to the front stringer 10. As a result the body is securely supported and braced against movement.

The passage-way through the chute 16 is preferably controlled by a gate 21, slidably mounted at the lower end of the body in guides 22, that are attached by suitable rivets to the side walls 13. The guides 22 terminate just below the bottom 15, so as to limit the downward movement of the gate. This gate is operated by a hand-lever 23, pivoted at one end to an arm 24, secured to the body and having a handle 25 at its other end. A link

25^a is pivotally connected at one end to the upper portion of the gate and at the other to an intermediate point on the lever, and thus it will be seen that when the lever is raised or lowered the gate will be correspondingly moved.

Below the bottom 15 is secured a screen 26, said screen being mounted in the following manner: The lower edges of the side walls 13 10 are provided with inwardly-extending guide-flanges 27, which constitute supports upon which the screen rests, said screen being removable through the lower end of the body. It is held in place by a hook 28, formed upon 15 the upper end of a hanger-rod 29, that passes through the upper end of the screen and the depending end wall 30 of the body. This hanger-rod 29 forms a support for the inner end of a slack-coal receptacle in the form of 20 a table or platform 31, having upstanding side flanges 32, said table being hinged at its front end to the lower end of the screen 26, its rear end detachably engaging a hook 33, formed upon the lower end of the hanger-rod. 25 By this construction it will be seen that the space between the bottom 15 and the screen 26 constitutes another chute, which is located beneath and inclined in the same direction as the chute 16, and that said screen 30 forms a bottom for this lower chute. Communication is afforded between the two chutes by an opening 34, located in the upper end of the bottom and arranged to be closed by a gate 35, slidably mounted in guides 36, secured to the under side of said bottom. The gate 35 is operated by means of a hand-lever 37, that passes through slots 38 in the side walls and is pivoted at one end to an outstanding arm 39, while its other end is formed 40 into a suitable handle 40. A link 41 connects the lever and the gate.

In Figs. 6 and 7 a slightly-modified form of the invention is illustrated, which is substantially as shown in daily use and is proving entirely satisfactory in operation. In this instance the upper chute is in all respects the same, comprising the side walls 13, a top 14, and a bottom 15^a, which bottom is located at the lower edges of the side walls. Instead of 45 separate hanger-braces 20 the support at the front end of the body is in the form of a stirrup 20^a, made of a strap that surrounds said body and is secured at its upper end to the front stringer 10. The bottom is provided 50 with the usual opening 34^a. The screen-chute (designated 26^a) instead of forming a part of the body is entirely separate from the same, but is directly beneath and occupies the same 55 relation as in the above-described construction. It comprises a screen-bottom 26^b, having upstanding side walls or flanges 26^c, thus forming a chute, the upper and lower ends of which are open. The upper end of this chute is provided with hooks 28^a, which detachably 60 engage eyes 28^b, secured to the rear stringer 10 directly beneath the platform, and the lower end of the screen is adjustably supported by

chains 42, secured to the front stringer 10 and arranged to be detachably engaged by hooks 43, located at the lower end of the screen. 70

By this arrangement it will be seen that the screen-chute is as readily detachable as in the first-described construction, and, furthermore, its angle of inclination can be changed by engaging the hook 43 at different points 75 of the chain 42. The slack-coal apron receptacle 31 is hinged at its front end to the screen 26^a in the usual manner, and its rear end detachably engages a hook 33^a of the hanger-rod 29^a. This illustrates but one modification of the invention, and it will be understood that other changes of construction may be made within the scope of the claims. 80

The operation of the device will be readily apparent. The car to be unloaded is placed 85 directly above the receiving end of the body, which constitutes a common mouth for both chutes, and the hopper of said car is opened, so as to permit the discharge of coal into the chute 16, the gates 21 and 35 being first closed. 90 As a result the chute 16 will be filled, whereupon the discharge of coal from the car will be stopped. A wagon is then backed under the discharge end of the body, and if the coal is to be put up in stock the gate 21 is raised 95 by operating the lever 23, thus permitting the coal in an unscreened condition to pass out into the vehicle. After said vehicle is filled the gate is again lowered and the discharge of coal consequently stopped. If, however, 100 the coal is to be delivered immediately to customers, the wagon is placed beneath the discharge end of the body, as usual, but instead of raising the gate 21 the gate 36 is slid from beneath the opening 34, thus allowing the coal 105 to pass into the lower chute and over the screen 26, said coal discharging below the gate 21 into the vehicle. The slack coal, however, will drop through the screen and deposit upon the horizontal receptacle or table 31, thereby 110 avoiding any liability of its dropping into the wagon. When it is desired to relieve this receptacle or table of its contents, it is only necessary to place a vehicle beneath it and release its rear end, thus causing it to drop 115 and dump its load. When the screen becomes worn, as it necessarily will in the course of time, it may be readily removed by releasing the hook 28 and replaced by a new one.

By this means it will be seen that a simple 120 and inexpensive structure is provided, which obviates any intermediate handling of the coal, and will screen it or not, as desired. The specific arrangement of the two chutes is especially advantageous where "twin" trestles are employed, said trestles consisting of two elevated tracks arranged side by side. In such structures it very often happens that one trestle is employed by one party and another by another, and by the present device the entire screening and discharging apparatus is located beneath a single trestle. 125 130

From the foregoing it is thought that the construction, operation, and many advan-

tages of the herein-described invention will be apparent to those skilled in the art without further description, and it will be understood that various changes in the size, shape, proportion, and minor details of construction may be resorted to without departing from the spirit or sacrificing any of the advantages of the invention.

Having thus described my invention, what I claim as new, and desire to secure by Letters Patent, is—

1. In apparatus of the class described, independent chutes having a common receiving-mouth, one of said chutes having an imperforate bottom, the bottom of the other being perforate, and separate means for controlling the passage-way through each chute whereby the material may be passed through either chute and consequently delivered screened or unscreened.

2. In apparatus of the class described, independent chutes located one below the other, said chutes having communication with each other contiguous to their upper ends, and means for closing said communication.

3. In apparatus of the class described, independent chutes having a common receiving-mouth inclined in the same direction, the bottom of one chute being imperforate and that of the other being perforate, and means for controlling the passage-ways through said chutes so that material may be passed through either and thereby delivered in screened or unscreened condition.

4. In apparatus of the class described, independent chutes located one below the other and inclined in the same direction, the bottom of the upper chute being imperforate, and that of the lower being perforate, said chutes having separate discharge ends located one below the other, and separate means for controlling the passage-way through each chute so that the material may be passed through either and thereby delivered in screened or unscreened condition.

5. In apparatus of the class described, independent chutes having communication at their upper ends, one of said chutes having an imperforate bottom, the other being provided with a perforate bottom, and means for controlling the passage-way through each chute so that material may be passed through either and thereby delivered in screened or unscreened condition.

6. In apparatus of the class described, independent chutes located one below the other and inclined in the same direction, said chutes having communication at their upper ends, the bottom of one chute being imperforate and the bottom of the other being perforate, and means for controlling the passage-way through each chute, so that the material may be passed through either and thereby delivered in screened or unscreened condition.

7. In apparatus of the class described, independent chutes located one below the other

and inclined in the same direction, said chutes having communication with each other at their upper ends, means for closing the communication, and mechanism for controlling the passage-way through the upper chute.

8. In apparatus of the class described, independent chutes located one below the other and inclined in the same direction, said chutes having communication with each other at their upper ends, the bottom of the upper chute being solid and that of the lower being a screen, a slidably-mounted gate for closing the communication between the two chutes, and a movable gate for controlling the passage-way through the upper chute.

9. In apparatus of the class described, independent chutes located one below the other and inclined in the same direction, the upper chute having a solid bottom and the bottom of the lower chute being a screen, said chutes having communication with each other at their upper ends, a gate slidably mounted on the bottom of the upper chute and movable to close the communication between the two chutes, a hand-lever having a connection with the gate, a gate slidably mounted on the lower end of the upper chute to control the passage-way therethrough, and a lever having a connection with said latter gate to move the same.

10. In apparatus of the class described, an inclined body having side walls, a bottom secured to said side walls above their lower edges forming thereabove a chute, and a screen detachably secured to the lower edges of said side walls.

11. In apparatus of the class described, an inclined body having side walls provided along their lower edges with guides, a bottom secured to said side walls above their lower edges and forming a chute, and a screen detachably mounted upon the guides.

12. In apparatus of the class described, an inclined body having side walls provided along their lower edges with inturned supporting-flanges, a bottom secured to the side walls above their lower edges forming a chute, and a screen detachably mounted upon the supporting-flanges.

13. In apparatus of the class described, an inclined body having side walls, a bottom secured to said side walls above their lower edges and forming a chute, a screen detachably secured to the lower edges of the side walls, and a slack-coal receptacle mounted below the screen.

14. In apparatus of the class described, an inclined body having side walls, a bottom secured to the side walls above their lower edges forming a chute, a screen detachably secured to the lower edges of the side walls, a slack-coal receptacle having a pivotal connection with the lower end of the body, and a detachable hanger connecting the body and the other end of the receptacle.

15. In apparatus of the class described, in-

dependent chutes located one below the other and inclined in the same direction, the bottom of the upper chute being imperforate and that of the lower having a screen, the 5 bottom of the upper chute having an opening at one end to establish communication with the lower chute.

In testimony that I claim the foregoing as my own I have hereto affixed my signature in the presence of two witnesses.

VAN WERT BALDWIN JOHNSON.
